SCOURING APPARATUS

Charles A. Dreisbach, Yonkers, N. Y.

Application July 2, 1946, Serial No. 680,917

14 Claims. (Cl. 51—13)

1
The present invention relates to improvements in scouring apparatus of the type which serves to project scouring or cleaning media against articles which it is desired to scour or clean. The scouring media referred to may be in any suitable and effective form such, for instance, as abrasive particles, mixtures of abrasive particles with air and/or liquids, or in some instances air and/or liquids without abrasive particles.

One of the main objects of the present invention is to provide a superior scouring apparatus whereby articles may have substantially all of their various surface areas subjected to the impact of scouring media.

Another object of the present invention is to provide an apparatus of the character referred to, and having a superior construction and arrangement of parts whereby a plurality of articles may be shifted in a simple, reliable and effective manner to expose their various surface areas to the impact of a scouring media.

A further object of the present invention is to provide a superior scouring apparatus so constructed and arranged that the articles being cleaned or scoured are caused to rub against each other while receiving the impact of scouring media, to thus facilitate the cleaning action.

A still further object is to provide a superior apparatus of the character referred to, whereby a plurality of articles may be shifted with respect to each and while being so shifted, subjected to the impact of scouring media and in which apparatus simple, reliable and effective means is provided for re-circulating the scouring media.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a view in side elevation of one form of scouring apparatus embodying the present invention;

Fig. 2 is a view thereof in front elevation;

Fig. 3 is a top or plan view thereof;

Fig. 4 is a transverse sectional view on an enlarged scale taken on the line 4—4 of Fig. 2;

Fig. 5 is a transverse sectional view taken on line 5—5 of Fig. 4;

Fig. 6 is a view in front edge elevation of the unit comprising the pan or container together with its track;

2

Fig. 7 is a broken detail sectional view taken on the line 7—7 of Fig. 6, but on a larger scale;

Fig. 8 is a broken detail sectional view taken on the line 8—8 of Fig. 4, but on a larger scale;

Fig. 9 is a view in side elevation of the scouring-head, detached;

Fig. 10 is a sectional view taken on the line 10—10 of Fig. 9; and

10 Figs. 11 to 14 inclusive are plan views schematically illustrating various phases of the gyrating movement of the pan or container.

The particular scouring apparatus chosen for illustration in the accompanying drawings for purposes of making clear a preferred form of the 15 present invention, includes a casing generally designated by the reference character 15 which, save for features as will be hereinafter described, is substantially airtight and may be conveniently formed of welded sheet metal. The said casing 15 includes a front wall 16, a back wall 17, complementary side walls 18 and 19, a top wall 20 and a bottom wall 21.

Extending from side to side across the top of 25 the casing 15 and in spaced relation above the top wall 20 thereof, are two similar head-frames 22—22 supported at their respective opposite ends on pairs of vertical posts 23—23 and 24—24 respectively secured to the outer faces of the side walls 18 and 19. Suitable diagonal bracings 25 30 are preferably also employed adjacent each of the side walls 18 and 19 to give the desired rigidity to the structure.

35 Welded or otherwise rigidly secured to the underfaces of the head-frames 22—22, is a head-bearing 26 in which rotates a vertical gyrator-drive tube 27. At its upper end in a plane above the head-frames 22—22, the said tube 27 has rigidly attached to it a worm-wheel 28 which is meshed into and driven by a worm 29 secured to 40 a horizontal drive-shaft 30 adjacent the rear end thereof, as is indicated in Fig. 3. At its forward end, the drive-shaft 30 is connected to and driven by an electric motor 31 which is preferably of the reduction-gear type. Both the worm 29 and 45 the electric motor 31 are carried by a mounting-plate 32 which is rigidly mounted upon the upper surfaces of the head-frames 22—22.

The lower end of the gyrator-drive tube 27 extends into the interior of the casing 15 through 50 a relatively-large-diametered opening 33 formed centrally in the top wall 20 of the said casing. Rigidly mounted upon the lower end of the tube 27 is a disk-like closure-plate 34 having a diameter slightly larger than the diameter of the opening 33, and so located as to slidably engage the

under-face of the top wall 20 at the portion there-of immediately surrounding the opening 33, as is indicated in Fig. 4.

At a point intermediate the upper surface of the top wall 20 and the lower edge of the head-bearing 26, the inner portion of a gyrator-arm 35 is rigidly secured to the exterior of the rotary gyrator-drive tube 27. At its outer end, the said gyrator-arm 35 is provided with a gyrating bearing 36 having its longitudinal axis inclined downwardly-and-inwardly toward the axis about which the gyrator-drive tube 27 turns, all as is indicated in Fig. 4.

Bodily movable with and rotatably mounted in the gyrating bearing 36 above referred to, is an inclined driveshaft 37 having its lower end projecting through and rotating in the closure-plate 34 and having its projecting upper end provided with a multi-groove drive-pulley 38. Extending around the drive-pulley 38 is a plurality of V-belts 39 which also extend around a multi-groove drive-pulley 40 driven by an electric motor 41 secured to the outer portion of the gyrator-arm 35 and bodily movable therewith.

The lower or inner end of the inclined drive-shaft 37 fits within and is keyed to a tubular neck 42 centrally projecting upwardly from the upper member 43 of a rotary scouring-head generally designated by the reference character 44. The scouring-head 44 just referred to also includes a lower member 45 which has an upper face generally of convex form and snugly interfitting with the generally-concave under-face of the upper member 43. Preferably and as shown, a slidable sleeve 46 fits over the drive-shaft 37 and the neck 42 at the point of their junction, to exclude foreign matter.

The concave under-face of the upper member 43 and the upper-face of the lower concavo-convex member 45 of the scouring-head 44 are each complementally grooved to provide the said scouring-head with a plurality of substantially-radial passages 47, for purposes as will herein-after appear. The outer ends of the said passages 47 each intersect the peripheral edge of the scouring-head while the inner ends of the said passages are each curved downwardly and intersect the upper end of an axial feed-passage 48 formed jointly in the lower member 45 and in a tubular stem 49 projecting downwardly from the said lower member in coaxial relationship with respect to the drive-shaft 37.

As will be apparent from the foregoing, the upper and lower members 43 and 45 are separable from each other in an axial direction to thus provide for convenient replacement and repair and also to permit the replacement of liners for the passages 47, when such liners are employed.

The tubular stem 49 above referred to extends downwardly into the inclined tubular upper portion 50 of a bearing-head generally designated by the reference character 51. The said upper portion 50 is coaxial with respect to the drive-shaft 37 and the gyrating-bearing 36. Suitable antifriction bearings such as 52 are interposed between the tubular stem 49 and the tubular upper portion 50 of the bearing-head 51, as is indicated in Fig. 4.

The bearing-head 51, in addition to its tubular upper portion 50, also includes a tubular lower portion 53 of a larger diameter than the said upper portion, and arranged coaxially with respect to the gyrator-drive tube 27 at the upper end of the structure.

The tubular lower portion 53 of the bearing-head 51 above referred to, is provided interiorly with suitable antifriction material 54 which turns upon a hollow bearing-stud 55 located within the casing 15 at a point about midway the height thereof and supported on a suitable frame-structure 56 connected to the lateral walls of the casing 15 in any suitable manner as, for instance, by welding.

Extending completely across the interior of the casing 15 at a point below the bearing-head 51 is a screen-plate 57 having its apertures opening downwardly into the upper end of a conical hopper 58 which tapers downwardly-and-inwardly toward a point which is coaxial with respect to the axis of the gyrator-drive tube 27 at the upper end of the structure, all as will be apparent by reference to Fig. 4.

The feed-passages 48 in the lower member 45 of the scouring-head 44 opens into the interior of the tubular bearing-stud 55 and into the expanded upper end of a vertical feed-tube 59 coaxial with the said bearing-stud 55 and extending downwardly through the disk-like bottom wall 60 of the hopper 58. The said bottom wall is welded or otherwise rigidly attached to the lower end of the hopper 58 and, in turn, has the upper edge of a cup-shaped member 61 welded to its under-face. The said member 61 is provided with a series of apertures 62 in its side wall. Encircling the side wall of the said member 61, is a regulating-ring 63 (Figs. 4 and 8) also provided with a series of apertures 64 which are adapted to be moved more or less into registry with the apertures 62 in the member 61, for purposes as will hereinafter appear.

For the purpose of turning the regulating-ring 63 with respect to the member 61 to thus vary the degree of registry of its apertures 63 with respect to the apertures 62, a link 65 is pivotally connected at its inner end to the said regulating-ring and is extended outwardly through the wall 19 of the casing 15 into a position convenient for manual manipulation.

The disk-like bottom wall 60 of the hopper 58 is provided with an annular series of apertures 66 through which scouring material may pass from the said hopper 58 into the cup-shaped member 61 for passage upwardly through the feed-tube 59, all in a manner as will herein-after appear. For the purpose of regulating the effective area of the apertures 66 in the bottom wall 60 of the hopper 58, a ring-like regulating-plate 67 is mounted against the upper face of the bottom wall 60 with capacity for being turned with respect thereto.

The regulating-plate 67 above referred to, is formed with an annular series of apertures 68 each of which is adapted to be moved more or less into registry with an individual aperture 66 in the bottom wall 60. Surrounding the lower portion of the feed-tube 59 and rigidly connected at its lower end to the regulating-plate 67, is an adjusting-tube 69 by means of which the said regulating-plate may be turned. Pivotally connected to the upper portion of the adjusting-tube 69 is the inner end of a link 70 having its outer end projecting through the side wall 19 of the casing 15 into a position for convenient manipulation.

Mounted for rotation upon the upper portion 50 of the bearing-head 51 is a bearing-member 71 having suitable antifriction material 72 interposed between it and the bearing-head 51.

The bearing-member 71 is provided with a plu-

rality of radial arms 73 which may be welded or otherwise secured to the conically-contoured central portion 74 of an article-container, in the form of a pan generally designated by the reference character 75. In addition to its conical central portion 74, the pan 75 includes a perforated bottom wall 76 and a substantially-annular side wall 77.

By means of the bearing-member 11, the pan 75 may be permitted to rotate with respect to the upper portion 50 of the bearing-head 51, should such rotation be desired.

Rigidly attached to the under-face of the pan 75 concentrically with respect to the drive-shaft 37 and associated parts, is a track-ring 78 which is preferably provided with an annular series of teeth 79.

The track-ring 78 of the pan 75 engages with a similar track-ring 80 carried by the frame-structure 56 and preferably having upwardly-extending teeth 81 adapted to be meshed into by the teeth 79 of the track-ring 78, in a manner as will hereinafter appear.

The pan 75 above referred to, is designed and adapted to receive a plurality of articles to be scoured, and to provide for the convenient discharge of such articles after the same have been scoured or cleaned, the flange-like side wall 77 is provided with a discharge-opening 82 which is normally closed by a removable gate 83. For the purpose of providing for the convenient removal of the gate 83 just referred to, the same has rigidly secured to its upper end a transverse retaining-bar 84 formed at each of its oppositely-projecting ends with downwardly-opening notches 85—85 adapted to fit over retaining-studs 86—86 located on the outer face of the pan 75 respectively on opposite sides of the discharge-opening 82 therein, as is clearly illustrated in Fig. 6. Secured to the lower portion of the gate 83, is a retaining-bar 87 corresponding to the retaining-bar 84 above described and formed in each of its projecting opposite ends with one of two notches 88—88 respectively fitting over retaining-studs 89—89 corresponding to the retaining-studs 85—85 and projecting outwardly from the lower portion of the side wall 77. The gate 83 may be removed by lifting the same upwardly, to thus leave the discharge-opening 82 in the pan 75 entirely clear.

Rigidly secured to the inner face of the front wall 16 of the casing 15 immediately above the screen-plate 57 thereof, is a discharge-chute 90 which is inclined outwardly-and-downwardly and has its inner edge located in a position to register with the bottom wall 76 of the pan 75 when the said pan is tilted into the position illustrated in Fig. 4. Immediately above the discharge-chute 90, the front wall 16 is formed with a discharge-opening 91 which is normally closed by a discharge-trough 92 pivoted adjacent its lower end to the casing 15 and normally held in its closed position by a latch 93, as is indicated in Fig. 4. When the said discharge-trough 92 is swung downwardly into the position shown by full lines in Figs. 1, 2 and 3 and by broken lines in Fig. 4, it registers with and forms a continuation of the discharge-chute 90.

Rigidly secured to the inner face of the front wall 16 is a downwardly-and-inwardly-inclined loading-chute 94 which extends into a position to cause articles to fall into the pan 75 when the latter is in the position in which it is indicated in Fig. 4. Formed in the front wall 16 and extending upwardly from the outer end of the load-

ing-chute 94 is a loading-opening 95 which is normally closed by a loading-trough 96. The said loading-trough is pivoted to the casing 15 adjacent its lower end, and is releasably held in its closed position (Fig. 4) by a latch 97.

The particular scouring apparatus illustrated and above described in detail is primarily designed to project scouring media in the form of abrasive particles mixed with air, though available for projecting other forms of scouring or cleaning media.

For the purpose of admitting air for passage upwardly through the feed-tube 59 etc., the front wall 16 of the casing 15 is provided with an air-inlet opening 98 located in a plane below the junction between the conical hopper 58 and the various lateral walls of the casing 15, so as to be sealed off, in effect, from the part of the interior of the said casing which is located above the said hopper.

Operation

For purposes of description, let it be assumed that the pan 75 is tilted into the position in which it is most clearly shown in Fig. 4 and that the discharge-trough 92 is swung upwardly into position to close the discharge-opening 91. It may be further assumed that the loading-trough 96 is unlatched and swung downwardly into the position shown by full lines in Figs. 1, 2, 3 and 5 and by broken lines in Fig. 4.

Metal castings or other articles to be scoured or cleaned may now be placed upon the upper surface of the loading-trough 96 for descent by gravity across the loading-shute 94 and thence into the pan or container 75.

After loading the articles into the pan 75, the loading-trough may be swung upwardly and latched in position to close the loading-opening 95, as is shown in Fig. 4.

The motor 31 may now be energized to effect the turning of the gyrator-drive tube 27 at a relatively-slow rate such, for instance, as three or four R. P. M.

The turning of the tube 27 will cause the gyrator-arm 35 to swing around at a similar rate of speed, carrying with it the motor 41, the drive-shaft 37 and connected parts, and will cause the bearing-head 51 to turn upon the hollow bearing-stud 55.

The turning movement above referred to will cause the pan or container 75 to progressively tilt in different directions, in the manner schematically illustrated in Figs. 11 to 14 inclusive, to thus substantially continuously cause the articles to be scoured to shift with respect to each other and with respect to the said pan.

The gyrating movement of the pan or container 75, as above described, will not cause the same to rotate with respect to the bearing-head 51 by which it is carried, so long as the pitch diameters of the two toothed track-rings 78 and 80 are the same. Should it be desired to have relative rotation take place, the said track-rings 78 and 80 may be differentiated in pitch diameter, to thus cause such rotation as the pan 75 is gyrated.

When the motor 41 is energized, it will cause the drive-shaft 37 to turn about its inclined axis while the said drive-shaft is being bodily carried around by the gyrator-arm 35. The turning of the drive-shaft 37 will, in turn, effect the rotation of the scouring-head 44 preferably at a peripheral speed well above one thousand feet

When the scouring-head 44 is rotated at high speed, it will serve to expel air by centrifugal force outwardly through its radial passages 47, and thus cause an up-draft through the feed-passage 48 in its tubular stem 49 and also in the feed-tube 59 with which the said feed-passage 48 communicates. In this manner, air entering the casing 15 through the air-inlet opening 98 in the casing 15, will be drawn at high speed through the apertures 64 in the regulating-ring 63, thence through the apertures 62 in the cup-shaped member 61 into the interior of the said member for movement upwardly through the feed-tube 59.

As air is being drawn into the interior of the cup-shaped member 61, as above described, abrasive particles (such, for instance, as crushed steel shot, sand, etc.), may be permitted to enter the said cup-shaped member through the apertures 68 in the regulating-plate 67 and through the apertures 66 in the bottom wall 60 of the hopper 58 for mixture with the said air and for movement therewith upwardly through the feed-tube 59. The mixture of air and abrasive particles moving upwardly through the feed-tube 59 will also pass upwardly through the feed-passage 48 of the scouring-head 44 and thence outwardly at high speed through the various radial passages 47 of the said scouring-head for impingement against the constantly-shifting mass of articles contained within the now-gyrating pan or container 75.

In the manner above described, the articles contained in the pan 75 or its equivalent will be substantially constantly shifted with respect to the said pan and with respect to each other while being subjected to a blast of abrasive particles being thrown out at high speed through the radial passages 47 in the scouring-head 44, to thus effect rapid, thorough and economical scouring.

As the pan or container 75 is gyrated, the cleaning media will work its way downwardly through the perforations in the bottom 76 of the said pan and thence back into the hopper 58 for re-use. Dust, etc., may be exhausted through the gyrator-drive tube 27.

The ratio of abrasive particles to air may be adjusted by appropriately shifting the aperture 64 with respect to the apertures 62 and the apertures 68 with respect to the apertures 66, in the manner before described.

Instead of subjecting the articles in the pan or container 75 to the action of a mixture of air and abrasive particles, such articles, when desired, may be subjected to the action of the air, water or mixtures of water, air and/or abrasive particles or other scouring or cleaning media or mixtures thereof.

After the completion of the cleaning or scouring operation, the motor 41 may be shut off to thus stop the rotation of the scouring-head 44, and similarly the motor 31 may be shut off to stop the gyratory movement of the pan or container 75. Preferably, the motor 31 will be shut off at such time as to cause the upper end of the drive-shaft 37 to lean toward the front of the casing 15 when it comes to rest, to thus bring the discharge-opening 82 in the pan 75 into registry with the discharge-opening 91 in the front wall 16. By having the pitch diameter of the track-ring 78 (and hence its number of teeth) corresponding to the pitch diameter (and hence in its number of teeth) of the track-ring 80, there will be assurance that the discharge-opening 82 in the pan 75 will register with the discharge-opening 91 in the front wall 16 when the gyrator-arm 35 is stopped so as to extend directly

forwardly, as is indicated in Figs. 1 to 4, inclusive.

The discharge-trough 96 may now be unlatched and swung downwardly into the position in which it is shown by full lines in Figs. 1 and 2 and by broken lines in Fig. 4. The gate 83 may now be removed from out of the discharge-opening 82 in the side wall 71 of the pan 75, to permit the now cleaned articles to move out of the said pan by gravity, assisted, if necessary, by a manual raking action.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A scouring apparatus, including in combination: a gyratory container constructed and arranged to contain a plurality of articles to be scoured; gyrating-means constructed and arranged to progressively tilt the said gyratory container in diverse directions to cause the articles contained therein to change position with respect to each other; cleaning-media-projecting means for projecting cleaning-media against the contents of the said gyratory container as the said contents change position as a result of the gyration of the said container; and means for progressively tilting the said cleaning-media-projecting means as the said container progressively tilts in different directions.

2. A scouring apparatus, including in combination: a container constructed and arranged to contain a plurality of articles to be scoured and having a bottom tilted at an angle which is intermediate the horizontal and vertical planes; gyrating-means constructed and arranged to progressively change the direction of tilt of the bottom of the said container to cause the articles contained in the latter to change position with respect to each other; cleaning-media-projecting means for projecting cleaning-media against the contents of the said container as the said contents change position as the result of the change in direction of tilt of the bottom of the said container; and means for progressively tilting the said cleaning-media-projecting means as the tilt of the said bottom progressively changes in direction.

3. A scouring apparatus, including in combination: a gyratory container having a substantially-annular track and constructed and arranged to contain a plurality of articles to be scoured; a substantially-annular supporting-track engaged by the track of the said container but arranged at an angle with respect thereto; gyrating-means constructed and arranged to progressively tilt the said gyratory container in diverse directions to cause the articles contained therein to change position with respect to each other and to progressively engage different portions of the said track with the said supporting-track; cleaning-media-projecting means for projecting cleaning-media against the contents of the said gyratory container as the said contents change position as a result of the gyration of the said container; and means for progressively tilting the said cleaning-media-projecting means as the said container progressively tilts in different directions.

4. A scouring apparatus, including in combination: a container constructed and arranged to contain a plurality of articles to be scoured and having a bottom wall tilted in an angle which is intermediate the horizontal and vertical planes; a substantially-annular track connected to the said bottom; a substantially-annular supporting-track engaged by the track of the said bottom but arranged at an angle with respect thereto; gyrating-means constructed and arranged to progressively change the direction of tilt of the bottom of the said container to cause the articles contained in the latter to change position with respect to each other and to progressively engage different portions of the said track with the said supporting-track; cleaning-media-projecting means for projecting cleaning-media against the contents of the said container as the said contents change position as the result of the change in direction of tilt of the bottom of the said container; and means for progressively tilting the said cleaning-media-projecting means as the bottom of the said container has its direction of tilt progressively changed.

5. A scouring apparatus, including in combination: a gyratory container constructed and arranged to contain a plurality of articles to be scoured; gyrating-means constructed and arranged to progressively tilt the said gyratory container in diverse directions to cause the articles contained therein to change position with respect to each other; rotary cleaning-media-projecting means constructed and arranged to project cleaning-media against the contents of the said gyratory container; and drive-means operatively connected to the said cleaning-media-projecting means to rotate the same with respect to the said gyratory container.

6. A scouring apparatus, including in combination: a gyratory container constructed and arranged to contain a plurality of articles to be scoured; gyrating-means constructed and arranged to progressively tilt the said gyratory container in diverse directions to cause the articles contained therein to change position with respect to each other; rotary cleaning-media-projecting means constructed and arranged to project cleaning-media against the contents of the said gyratory container; drive-means operatively connected to the said cleaning-media-projecting means to rotate the same with respect to the said gyratory container; and means progressively tilting the said cleaning-media-projecting means as the same rotates and as the said container progressively tilts in different directions.

7. A scouring apparatus, including in combination: a container constructed and arranged to contain a plurality of articles to be scoured and having a perforated bottom tilted at an angle which is intermediate the horizontal and vertical planes; a hopper located beneath the perforated bottom of the said container; gyrating-means constructed and arranged to progressively change the direction of tilt of the bottom of the said container; cleaning-media-projecting means for projecting cleaning-media against the contents of the said container; and cleaning-media-feed-means extending substantially centrally through the said container and communicating at its opposite ends with the said cleaning-media-projecting means and the said hopper respectively.

8. A scouring apparatus, including in combination: a container constructed and arranged to contain a plurality of articles to be scoured and

having a perforated bottom tilted at an angle which is intermediate the horizontal and vertical planes; a hopper located beneath the perforated bottom of the said container; gyrating-means constructed and arranged to progressively change the direction of tilt of the bottom of the said container; cleaning-media-projecting means for projecting cleaning-media against the contents of the said container; cleaning-media feed-means extending substantially centrally through the said container and communicating at its opposite ends with the said cleaning-media-projecting means and the said hopper respectively; and means progressively tilting the said cleaning-media-projecting means as the tilt of the said perforated bottom progressively changes in direction.

9. A scouring apparatus, including in combination: a container constructed and arranged to contain a plurality of articles to be scoured and having a perforated bottom tilted at an angle which is intermediate the horizontal and vertical planes; a hopper located beneath the perforated bottom of the said container; gyrating-means constructed and arranged to progressively change the direction of tilt of the bottom of the said container; rotary cleaning-media-projecting means for projecting cleaning-media against the contents of the said container; drive-means operatively connected to the said cleaning-media-projecting means to rotate the same with respect to the said gyratory container; and cleaning-media feed-means extending substantially centrally through the said container and communicating at its opposite ends with the said cleaning-media-projecting means and the said hopper respectively.

10. A scouring apparatus, including in combination: a container constructed and arranged to contain a plurality of articles to be scoured and having a perforated bottom tilted at an angle which is intermediate the horizontal and vertical planes; a hopper located beneath the perforated bottom of the said container; gyrating-means constructed and arranged to progressively change the direction of tilt of the bottom of the said container; rotary cleaning-media-projecting means for projecting cleaning-media against the contents of the said container; drive-means operatively connected to the said cleaning-media-projecting means to rotate the same with respect to the said gyratory container; cleaning-media feed-means extending substantially centrally through the said container and communicating at its opposite ends with the said cleaning-media-projecting means and the said hopper respectively; and means progressively tilting the said cleaning-media-projecting means as the tilt of the said perforated bottom progressively changes in direction.

11. A scouring apparatus, including in combination: a container constructed and arranged to contain a plurality of articles to be scoured and having a perforated bottom tilted at an angle which is intermediate the horizontal and vertical planes; a hopper located beneath the perforated bottom of the said container; gyrating-means constructed and arranged to progressively change the direction of tilt of the bottom of the said container; rotary cleaning-media-projecting means for projecting cleaning-media against the contents of the said container; drive-means carried for bodily movement by the said gyrating-means and operatively connected to the said cleaning-media-projecting means to rotate the

same with respect to the said gyratory container; and cleaning-media feed-means extending substantially centrally through the said container and communicating at its opposite ends with the said cleaning-media-projecting means and the said hopper respectively.

12. A scouring apparatus, including in combination: a container constructed and arranged to contain a plurality of articles to be scoured and having a perforated bottom tilted at an angle which is intermediate the horizontal and vertical planes; a hopper located beneath the perforated bottom of the said container; gyrating-means constructed and arranged to progressively change the direction of tilt of the bottom of the said container; rotary cleaning-media-projecting means for projecting cleaning-media against the contents of the said container; drive-means carried for bodily movement by the said gyrating-means and operatively connected to the said cleaning-media-projecting means to rotate the same with respect to the said gyratory container; cleaning-media feed-means extending substantially centrally through the said container and communicating at its opposite ends with the said cleaning-media-projecting means and the said hopper respectively; and means progressively tilting the said cleaning-media-projecting means as the tilt of the said perforated bottom progressively changes in direction.

13. A scouring apparatus, including in combination: a gyratory container constructed and arranged to contain a plurality of articles to be scoured; a substantially-vertical drive-member located above the said container; a gyrator-arm driven by and projecting laterally outwardly from the said drive-member and provided with bearing-means inclined downwardly and inwardly toward the axis about which the said drive-member turns; a drive-shaft rotating in the said bearing-means; a drive-motor operatively connected to the said drive-shaft and carried by the said gyrator-arm for bodily movement therewith; a rotary cleaning-media-projecting head substantially coaxial with and operatively connected to the said drive-shaft for being rotated thereby and positioned to project cleaning-media against the contents of the said container; means connecting the said gyratory container to the said drive-shaft with freedom for relative rotation therebetween and constructed and arranged to progressively tilt the said container as the said drive-shaft is bodily moved by the said gyrator-arm; and means for turning the said substantially-vertical drive-member to effect the swinging

movement of the said gyrator-arm and the bodily movement of the said drive-shaft and its said drive-motor.

14. A scouring apparatus, including in combination: a container adapted to contain a plurality of articles to be scoured and having a perforated bottom tilted at an angle which is intermediate the horizontal and vertical planes; a substantially-vertical drive-member located above the said container; a gyrator-arm driven by and projecting laterally from the said drive-member and provided with bearing-means inclined downwardly and inwardly toward the axis about which the said drive-member turns; a drive-shaft rotating in the said bearing-means; a drive-motor operatively connected to the said drive-shaft and carried by the said gyrator-arm for bodily movement therewith; a rotary cleaning-media-projecting head substantially coaxial with and operatively connected to the said drive-shaft for being rotated thereby and positioned to project cleaning-media against the contents of the said container; means connecting the said gyratory container to the said drive-shaft with freedom for relative rotation therebetween and constructed and arranged to progressively tilt the perforated bottom of the said container as the said drive-shaft is bodily moved by the said gyrator-arm; a hopper located beneath the said container; means for turning the said substantially-vertical drive-member to effect the swinging movement of the said gyrator-arm and the bodily movement of the drive-motor; and cleaning-media feed-means extending substantially centrally through the said container and communicating at its opposite ends with the said cleaning-media-projecting head and the said hopper respectively.

CHARLES A. DREISBACH.
